SHIRT OR SIMILAR GARMENT FOR SPORTSWEAR

George London, Brooklyn, N. Y.

Application November 16, 1953, Serial No. 27,625

Term of patent 14 years

(Cl. D3—25)

To all whom it may concern:

Be it known that I, George London, of Brooklyn, New York, have invented a new, original, and ornamental Design for Shirts or Similar Garments, for sportswear, of which the following is a specification, reference being had to the accompanying drawing, forming part thereof, wherein Figure 1 is a front elevational view of a shirt showing my new design; while Fig. 2 is a back view similar to Fig. 1.

I claim:

The ornamental design for a shirt or similar garment for sportswear, substantially as shown.
